CLAIM

The ornamental design for a combined hand and wrist article strap, as shown and described.

DESCRIPTION

FIG. 1 is an environmental perspective view of a combined hand and wrist article strap showing my new design, the portion of the figure shown in broken lines forming no part of the claimed design;

FIG. 2 is a front elevational view thereof;

FIG. 3 is a rear elevational view thereof;

FIG. 4 is a top plan view thereof;

FIG. 5 is a left elevational view thereof;

FIG. 6 is a right elevational view thereof; and,

FIG. 7 is a bottom plan view thereof.

FIG. I

FIG. 2

FIG. 3

FIG. 4

FIG. 7

FIG. 5

FIG. 6
